SET OF NESTED ASH TRAYS OR SIMILAR ARTICLE

Joe Bryan McKee, 9516 Loganberry Lane,
Everett, Wash. 98201

Filed May 15, 1969, Ser. No. 17,158

Term of patent 14 years

Int. Cl. D27—03

U.S. Cl. D85—2

Fig. 1.

Fig. 2.

FIG. 1 is a top perspective view of a set of nested ash trays or similar article, showing my new design; and

FIG. 2 is an exploded top perspective view thereof.

The bottom, not shown, is flat and unornamented.

I claim:

The ornamental design for a set of nested ash trays or similar article, substantially as shown and described.
